UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 921,214.

Specification of Letters Patent.

Patented May 11, 1909.

Application filed March 1, 1909. Serial No. 480,548.

To all whom it may concern:

Be it known that I, JACOB FELBEL, citizen of the United States, and resident of the borough of Manhattan, city of New York, 5 in the county of New York and State of New York, have invented certain new and useful Improvements in Type-Writing Machines, of which the following is a specification.

10 My invention relates to typewriting machines and more particularly to fractional line spacing devices involving platen clutches, and the invention has for its principal object to provide improved means for operating platen clutches.

15 My invention consists in certain features of construction and combinations and arrangements of parts, all of which will be fully set forth herein and particularly pointed out in the claims.

20 In the accompanying drawings, Figure 1 is a longitudinal central section through the platen of a typewriting machine having my invention embodied therein, part of the carriage being also shown and parts being broken away, and the clutch shown in normal or clutching position. Fig. 2 is a similar view of the end of the platen on which the line space wheel is mounted and some 25 of the connected parts, but showing the clutch in released position. Fig. 3 is an isometric view of one of the platen heads. Fig. 4 is a diagrammatic face view of the line space wheel and the dogs and wedges 30 of the clutch. Figs. 5 and 6 are bottom views showing part of the clutch operating mechanism detached, Fig. 5 showing the parts in normal position and Fig. 6 showing the parts in released position. Fig. 7 is a 35 side view of a guide piece forming part of the mechanism. Fig. 8 is an isometric view, on an enlarged scale showing a collar and pin.

40 My invention is applicable or adaptable 45 to various styles of typewriting machines and to various sorts of platen clutches, but I have here shown it applied to a Monarch typewriter and preferably to a platen clutch like that shown in the British patent to 50 Fell No. 28,219 of 1906. The platen clutch shown in said British patent, like most other platen clutches, is operated to release the platen from the line space wheel by moving a part longitudinally of the platen axle.

55 It is one of the purposes of the present invention to operate these clutches by a lever or other device that is mounted in the platen frame and situated in a more convenient position than these longitudinally movable parts and that moves in another direction 60 and will be automatically retained in either of the positions to which it is set, thus leaving the hands of the operator free to turn the platen or to adjust the paper or to do whatever else may be necessary while the 65 clutch is disconnected.

70 Operating devices that have to be moved by hand longitudinally of the platen, have usually involved a divided platen axle or some modification of the bearings or supports of the platen, which tend to complicate the mechanism and to weaken important parts of said mechanism. In some forms of these platen clutches the platen 75 knob or finger wheel itself is movable longitudinally; in others the platen shaft by means of the finger wheel. If the knob that has to be pushed is situated at the left-hand end of the platen, then, when said knob is operated, there is a liability to move the 80 platen backward in letter space direction.

One of the purposes of my invention is to operate the platen clutch by means not open to any of these several objections.

85 The carriage of the Monarch typewriter comprises two end pieces or brackets 1 and 2 which support the platen 3. Said platen is provided with a shaft 4 which is journaled in bearing sleeves 5 which pass through suitable openings in the brackets 1 and 2 90 where they are rigidly secured by set screws. 6. The platen is provided with a right-hand platen head 7 which is rigidly fixed to the shaft 4 by means of a set screw 8. In this machine the line space wheel is at the 95 left-hand end of the platen and the left-hand platen head 9 has the line space wheel 10 mounted thereon. The platen heads are secured to the wooden core of the platen by screws 11 which pass through holes 12 in the 100 platen heads. The shaft 4 is provided at its ends with the usual finger wheels 13. The left-hand face of the platen head 9 is formed with three projections 14 constituting segments of an annular flange the periphery of which is surrounded by the platen wheel 10 in such fashion that when 105 the clutch is released the line space wheel

and platen head are free to turn the one with relation to the other. The line space wheel has an internal flange in which internal V-shaped teeth 15 are formed and it is 5 the points of these teeth that ride on the peripheries of the flange segments 14. Three rectangular radial openings 16 between the segments 14, serve as guide ways for dogs 17 which are mounted in said openings 16 10 with freedom to slide radially in and out. Each of these dogs has at its outer end a chisel or V-shaped tooth 18 adapted to enter the notches between the teeth 15 of the line space wheel. These dogs are normally 15 pressed into engagement with the teeth 15 by means of wedges 20 which are seated in holes 21 formed longitudinally of the platen in an inward extension 22 of the platen head 9. The wedges 20 are pressed toward 20 the left by coiled springs 23 compressed between the bottoms of the holes 21 and the ends of the wedges 20. Each of said wedges has an inclined or wedge face 24 which contacts with a similarly inclined face on the 25 inner end of the corresponding dog 17. The spacing of the teeth 18 of the dogs and of the teeth 15 of the line space wheel, is such that in no relative positions of the platen and line space wheel can more than 30 one of the teeth 18 be bottomed in one of the notches between the teeth 15. In Fig. 4 the parts are shown in such a position that one of said teeth 18 is pressed to the bottom of one of the notches. When the platen 35 and line space wheel happen to occupy this relative position it will be noted that one of the other teeth 18 is pressed against one of the teeth 15 in such a way as to prevent relative motion of the line space wheel and 40 platen in one direction and the third tooth 18 engages one of the teeth 15 in such a way as to prevent relative motion of these parts in the other direction. The parts are so designed that in any relative position of the 45 line space wheel and platen at least one of the teeth 18 will prevent motion of the platen relatively to the line space wheel in one direction and at least one of said teeth will prevent relative motion of the parts in 50 the other direction, so that said line space wheel and platen are locked together to turn in unison. The angle of the inclined part 24 of each of the wedges is such that pressure inward on the corresponding dog 17 55 will not cam the wedge toward the right so that the dog is positively locked in its engaged position.

A retaining plate 25 is mounted on the platen head 9, being secured to the faces of 60 the flanged segment 14 by screws 26 threaded into screw-holes 27 in said flanges. This retaining plate closes the openings 16 so as to retain the dog 17 in place in said openings and it also lies over the internally 65 toothed flange of the line space wheel, thus

retaining said line space wheel in position. This retaining plate has a smooth periphery which forms part of the journal bearing for the line space wheel when said line space wheel is free to turn. The line space wheel 70 has crown ratchet teeth 28 which are engaged by the line space pawl (not shown) and also by the usual detent roller 29.

In order to release the platen clutch, a disk or collar 30 is slidably mounted on the 75 shaft 4 to the left of the platen head 9 and this disk is adapted to engage leftward prolongations 31 of the wedges 20 so that when the disk is moved toward the right it pushes all of said wedges toward the right and releases the dogs 17 from said wedges, leaving 80 said dogs free to move inward toward the shaft 4 to a sufficient extent to release them from the teeth 15. The disk 30 is formed with an internal coned surface 32 which, 85 when said disk is moved toward the right, is adapted to engage inclined surfaces 33 formed on the toes of the dogs 17, the construction being such that the coned surface 32 cams the dogs 17 positively inward out of 90 engagement with the teeth 15.

The disk or collar 30 is moved toward the right to release the platen by means of a handle or lever 34 which is rigidly mounted on or secured to a collar 35 which is journaled on the shaft 4 just inside of the sleeve 5. The collar 35 is bored out at its right-hand end so as to receive the disk 30 and the right-hand end of the collar 35 abuts the end of a hub portion 36 of the retaining 100 plate 25. The collar 35 is thus held against endwise motion, being mounted between the retaining plate 25 and the sleeve 5. A collar 37 is loosely mounted on the shaft 4 within the enlarged part of the collar 35 just at the 105 left of the collar 30. The collar 37 has a pin 38 projecting therefrom through a cam slot 40 in the sleeve 35. This cam slot has its middle part cut at an inclination as shown in Figs. 5 and 6 and at its ends it is 110 formed with dwells 41 and 42. The inner end of the slot is open when the collar 35 is detached from the machine but when the parts are assembled it is closed by the hub 36 as shown in Fig. 5. The pin 38 is prolonged beyond the collar 35 as shown in Fig. 1 and passes through an elongated slot 43 in an arm 44 which is rigidly secured to the platen frame in any suitable manner. As here shown this arm has a hole 45 (Fig. 7) 115 through which the screw 6 passes and the arm is held in place by a nut 46 which tightens the arm up against the bracket 1. The slot 43 extends parallel with the shaft 4 so that the pin 38 is free to move longitudinally of the platen but is not free to turn about the platen axis.

The handle 34 normally occupies its rear-most position shown in Fig. 1 and the pin 38 then occupies the dwell 41 as shown in 130

Fig. 5. If the handle 34 be pulled toward the front of the machine the sleeve 35 will rotate from the position shown in Fig. 5 to that shown in Fig. 6 and as the pin 38 can not rotate with the sleeve on account of the arm 44, said pin is cammed toward the right until it occupies the dwell 42 at the other end of the slot 40. The sleeve 37 is thus forced toward the right carrying the sleeve 10 30 with it and releasing the clutch, the parts then occupying the position shown in Fig. 2. As the pin 38 is then in a dwell in the cam slot the handle may be released and it will remain in that position until it is pushed 15 back to its normal position, or at least until it is pushed far enough to release the pin 38 from the dwell 42. While the handle is in this clutch-releasing position the platen may be turned to any desired extent independently of the line space wheel. When the platen has been turned to the desired position and the handle 34 has been pushed back to normal position, then the clutch automatically locks the platen and line space 20 25 wheel together in the precise relative position to which they were adjusted and the line spacing will proceed from that position.

I am aware that many changes may be made in the details of construction and arrangement without departing from my invention.

While I have here shown the cam 40 as moving concentrically with the shaft 4, yet this cam, of course, can move in other ways.

35 It will be noted that the clutch releasing element 30 of the platen clutch moves longitudinally of the platen and that the handle by which it is operated moves in a plane that is transverse to the platen axis.

40 What I claim as new and desire to secure by Letters Patent, is:—

1. In a typewriting machine, the combination of a rotary platen, a line space wheel, a releasable clutch normally locking said 45 line space wheel and platen to turn together, a handle movable in a plane transverse to the platen axis for releasing said clutch, and means connecting said handle with said clutch.

50 2. In a typewriting machine, the combination of a rotary platen, a line space wheel for said platen, a releasable clutch for normally causing said platen and line space wheel to turn together, a handle arranged

to be operated in a plane transverse to the 55 platen axis, and means operated by said handle for moving a part of said clutch longitudinally of the platen in order to release said clutch.

3. In a typewriting machine, the combination of a rotary platen, a line space wheel for said platen, a releasable clutch for normally causing said platen and line space wheel to turn together, a handle arranged to be operated in a plane transverse to the 60 platen axis, and a cam operated by said handle for moving a part of said clutch longitudinally of the platen in order to release 65 said clutch.

4. In a typewriting machine, the combination of a rotary platen, a line space wheel for said platen, a releasable clutch for normally causing said platen and line space wheel to turn together, a lever pivoted in the platen frame to move in a plane transverse of the platen axis, and means operated 70 by said lever for operating said clutch.

5. In a typewriting machine, the combination of a rotary platen, a line space wheel, a releasable clutch normally locking said 75 line space wheel and the platen to turn together, a handle movable in a plane transverse to the platen axis for releasing said clutch, means connecting said handle with said clutch and means for causing said handle to remain in either of the positions to which it may be moved.

6. In a typewriting machine, the combination of a rotary platen, a line space wheel for said platen, a releasable clutch for normally causing said platen and line space wheel to turn together, a handle arranged to be operated in a plane transverse to the 90 platen axis, a cam operated by said handle for moving a part of said clutch longitudinally of the platen in order to release said clutch, said cam having a dwell to allow 95 said handle to remain in clutch-releasing position.

Signed at the borough of Manhattan, city 100 of New York, in the county of New York and State of New York this 27th day of February A. D. 1909.

JACOB FELBEL.
